GUMMED TAPE DISPENSER

Harry Jackson Collins, Jr., Milwaukee, Wis., assignor to Tape, Inc., Green Bay, Wis., a corporation of Wisconsin

Application July 6, 1954, Serial No. 31,293

Term of patent 14 years

(Cl. D74—1)

Fig. 1

Fig. 3

Fig. 1 is a view in perspective of a gummed tape dispenser showing my new design.

Fig. 2 is a side elevational view of the device shown in Fig. 1. The opposite side presents the same appearance as the side shown.

Fig. 3 is a rear elevational view of the device shown in Fig. 1.

I claim:

The ornamental design for a gummed tape dispenser, as shown and described.
